CONSOLE FOR TAPE EQUIPMENT

Robert H. Eytel, Fishkill, and Hercules A. Volpe, Poughkeepsie, N.Y., assignors to International Business Machines Corporation, New York, N.Y., a corporation of New York

Filed Sept. 9, 1959, Ser. No. 57,495

Term of patent 14 years

(Cl. D26—5)

FIG. 1

FIG. 2

Fig. 1 is a perspective view of the front and right-hand side of a console for tape equipment showing our new design.

Fig. 2 is a perspective view of the rear and left-hand side thereof.

Portions of Fig. 1 are diagonally lined to indicate transparency.

We claim:

The ornamental design for a console for tape equipment, as shown and described.
